CLAUD L. BANKS AND ORIS W. SMITH, OF NEW PHILADELPHIA, OHIO

ROCKING HORSE

Application filed August 9, 1930. Serial No. 474,241.

This invention relates to a rocking horse, the general object of the invention being to provide a wheeled frame on which the rockers of the horse are carried, with means imparting movement to the frame by the rocking action of the horse so that the device will travel along as the horse is rocked, with means whereby the rider can steer the device.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

20 Figure 1 is an elevation of the device.

Figure 2 is a rear end view.

Figure 3 is a top plan view of the frame.

Figure 4 is a side view of the frame, with the rockers thereon.

25 Figure 5 is a section on line 5—5 of Figure 4.

Figure 6 is a view of one of the brackets for supporting the spring which connects a rocker with the frame.

30 In these views, the numeral 1 indicates a pair of side members which are preferably of angle iron, the rear end of each side member having a flat extension 2, the extensions being perforated to receive the rear shaft 3

35 to which the wheels 4 are connected. The front end of each side member is formed with an inwardly and upwardly extending part 5, these parts 5 being connected together to form an eye to receive a bolt 6 which passes

40 through the ears 7 on the diagonally arranged steering post 8 which carries the front wheel 9.

A rocker member 10, preferably of angle iron, engages each side member 1 and the legs of the horse A are fastened to the rocker members, as shown. Brackets 11 are fastened to the members 1 and the rocker members 10 and a spring 12 is arranged in each pair of brackets and has its ends fastened 45 to the pins 13 which pass through the brack-

ets. These springs tend to hold the rocker members with the horse in a normal position, but when the horse is rocked, the springs will facilitate rocking movement. A ratchet wheel 14 is fastened to the center of the rear shaft 3 and the teeth of this ratchet are engaged by the pins 15 carried by the front and rear pairs of members 16 which are pivotally connected at their upper ends to a shaft 17 which connects the rear ends of the 60 rockers together. Springs 18 connect the front and rear members together and tend to hold the pins against the teeth of the ratchet wheel. Thus as the horse is rocked on the frame, the downward movement of the 65 rear ends of the rockers will cause the pins of the front members 16 to rotate the wheel and the shaft 3, while the pins of the rear members will ratchet over the teeth and on the upward movement of the rockers, the pins 70 of the rear members will impart movement to the ratchet wheel, while the pins of the front members ratchet over the wheel. Thus the frame, composed of the members 1 and the front and rear wheels 4 and 9, will be 75 moved by the rocking movement of the horse. Reins 19 are connected to the prongs of the forked post 8 by the chains 21 so that the rider can steer the device as it moves along. Springs 22 connect the post with the side 80 members 1 and act to hold the front wheel in a straight position.

From the foregoing it will be seen that we have provided a rocking horse mounted on a wheeled frame, with means for causing the frame to move along a surface while the horse is being rocked, with means for steering the frame by the rider on the horse.

While the drawings show the invention as used with a rocking horse, it will, of course, be understood that it can be used with a chair or other seat forming member.

It is thought from the foregoing description that the advantages and novel features of the invention will be readily apparent.

It is to be understood that changes may be made in the construction and in the combination and arrangement of the several parts, provided that such changes fall within the scope of the appended claims.

What we claim is:—

1. A device of the class described comprising a frame, an axle at the rear of the frame, wheels carried by said axle, a rocking horse supported by the frame, a ratchet wheel for propelling said wheel, opposed members pivoted to the rocking horse and having ratchet pins for engaging the ratchet wheel for double ratchet action thereon on reverse movements of the horse, and means for tensioning said members to hold the same in operative relation to the ratchet wheel.
- 10 2. A device of the class described comprising a frame, an axle at the rear of the frame, wheels carried by said axle, a rocking horse supported by the frame, a ratchet wheel for propelling said wheel, opposed members pivoted to the rocking horse and having ratchet pins for engaging the ratchet wheel for double ratchet action thereon on reverse movements of the horse, means for tensioning said members to hold the same in operative relation to the ratchet wheel, and springs yieldably and swingingly connecting the rocking horse with the frame.
- 15 3. A device of the class described comprising a frame, an axle at the rear of the frame, wheels carried by said axle, a rocking horse supported by the frame, a ratchet wheel for propelling said wheel, opposed members pivoted to the rocking horse and having ratchet pins for engaging the ratchet wheel for double ratchet action thereon on reverse movements of the horse, means for tensioning said members to hold the same in operative relation to the ratchet wheel, springs yieldably and swingingly connecting the rocking horse with the frame, and housings on the frame and rocking horse to close said spring.
- 20 40 In testimony whereof we affix our signatures.

CLAUD L. BANKS.
ORIS W. SMITH.
